ELECTRIC SWITCH.

1,169,089.

Specification of Letters Patent.

Patented Jan. 18, 1916.

Application filed July 6, 1915. Serial No. 38,074.

To all whom it may concern:

Be it known that we, BURTON L. LAWTON and BENJAMIN A. SPITZER, citizens of the United States of America, residing at Meriden, New Haven county, Connecticut, have invented a new and useful Electric Switch, of which the following is a specification.

Our invention relates to improvements in electric switches, and particularly to a simple form thereof, which is easy to assemble, inexpensive, durable and effective.

In the drawings: Figure 1 is a side elevation of the complete switch. Fig. 2 is a central longitudinal section. Fig. 3 is a cross section on the line 3—3. Fig. 4 is an end view of the insulating block with the cover plate and switch plug removed. Figs. 5 and 6 are details in perspective.

1 is a block of insulating material having a central cavity in which are located spring contacts 2—2. In the bottom of the cavity is a backing shoulder 3. The lower end of each spring contact piece 2—2 has an outwardly bent foot 4. The upper end of each 20 of said spring contacts is bent inwardly so that between the bent-in ends may be located and properly held a switch plug. The switch plug preferably comprises the tapered metallic end piece 5, and the insulating shank 6.

7 is an annular notch in the insulation 6.

The spring contacts are held in place by an ingenious and simple combined holding means and terminal member in the form of 35 a specially constructed tubular member 8 having a flange 9, the shank of the tubular member being arranged to pass through a hole in the foot of its respective spring contact, and to continue on through a hole in 40 the base or inner end of the block 1. One side of the flange is cut away so as to bear flatwise against the adjacent upstanding part of the spring contact held thereby.

10 is a washer which is by preference used 45 at the outer end of the tubular connecting means 8. In assembling, the tubular connecting means is passed through its hole in the foot 4 and through the passage in the base of the block 1. The washer 10 is then 50 slipped into place and the outer end of the tubular member 8 is spun outwardly so as to permanently unite the parts. The action of the spinning tool against the end of the member 8 would, of course, tend to rotate

the same, but rotation is prevented since the 55 squared shoulder on the member 8 bears against the adjacent upstanding part of the spring contact 2, which latter cannot turn in the base, and hence, holds the member 8 against rotation, thus permitting the spinning operation to be reliably effected. By reason of this construction a tap may also be passed through the tubular member 8 to form a thread to receive a binding screw (not shown) so that each tubular member 8 60 65 may perform the function of a binding post or terminal.

11 is a cover plate or escutcheon which may be secured to the outer end of the block 1, in any suitable manner as by screws 70 12—12. The outer end of the plug is provided with a handle 14 so that by pulling out the plug, the metallic end 5 may electrically bridge and connect the ends of the contacts 2—2, or, by pushing in the plug, the insulating plug shank may be caused to rest between and electrically disconnect the two 75 spring contacts.

The notch in the insulating shank serves to prevent the accidental displacement of 80 the plug, and to hold the contacts in the open circuit position. The tapered metallic tip likewise is gripped by the spring contacts in such a way as to hold the plug in the closed circuit position when the plug has 85 been shifted manually thereto.

We have shown the invention in its preferred form and it will be seen to comprise very few and exceedingly simple parts, all of which are quickly and effectively assembled or united in their respective positions ready for operation.

What we claim is:

1. In an electric switch of the character described, a block of insulating material having a longitudinal cavity therein open at one end, a pair of spring contacts seated in the bottom of said cavity, each of said spring contacts having a laterally extending foot at its lower end, with means engaging said foot for holding said contact against turning in said cavity, a tubular connecting member for each of said contacts, each of said members passing through said foot and through the lower end of said block and upset externally of the latter, with means for holding said tubular member against turning relatively to its contact, said means com- 95 100 105

prising a flanged shoulder at the inner end of said tubular member, said flange bearing against that part of the contact just above said foot.

- 5 2. In an electric switch of the character described, a block of insulating material forming an insulating base, a spring contact mounted on said base having a laterally extending foot portion engaging the base, a

10 shoulder on the base engaging said foot por-

tion and holding the contact against turning on the base and a tubular connecting member passed through the base and the laterally extending foot portion of the contact, said connecting member having a flanged 15 shoulder engaging the contact above the foot portion thereof to secure said tubular member against turning on the base.

BURTON L. LAWTON.
BENJAMIN A. SPITZER.
